US0D1014780S

(12) **United States Design Patent** (10) **Patent No.:** **US D1,014,780 S**
(45) **Date of Patent:** **** Feb. 13, 2024**

(54) **CUVETTE**

(71) Applicant: **Instrumentation Laboratory Co.,**
Bedford, MA (US)

(72) Inventors: **Ethan F. Schonbrun**, Auburndale, MA (US); **Christopher Farren**, Bedford, MA (US); **Paul C. McCormack**, Carlisle, MA (US); **Luisa Andruzzi**, Bedford, MA (US)

(73) Assignee: **Instrumentation Laboratory Co.,**
Bedford, MA (US)

(**) Term: **15 Years**

(21) Appl. No.: **29/835,071**

(22) Filed: **Apr. 15, 2022**

(51) LOC (14) Cl. **24-02**

(52) U.S. Cl.

(57) **CLAIM**

The ornamental design for a cuvette, as shown and described.

DESCRIPTION

FIG. 1 is a top perspective view of a first embodiment of a cuvette, showing our new design;

FIG. 2 is a bottom perspective thereof;

FIG. 3 is a right side view thereof;

FIG. 4 is a left side view thereof;

FIG. 5 is a front view thereof;

FIG. 6 is a rear view thereof;

FIG. 7 is a top view thereof; and

FIG. 8 is a bottom view thereof.

FIG. 9 is a top perspective view of a second embodiment of a cuvette;

FIG. 10 is a bottom perspective thereof;

FIG. 11 is a right side view thereof;

FIG. 12 is a left side view thereof;

FIG. 13 is a front view thereof;

FIG. 14 is a rear view thereof;

FIG. 15 is a top view thereof; and

FIG. 16 is a bottom view thereof.

FIG. 17 is a top perspective view of the first embodiment in a cuvette array;

FIG. 18 is a bottom perspective thereof;

FIG. 19 is a front view thereof;

FIG. 20 is a rear view thereof;

FIG. 21 is a right side view thereof;

FIG. 22 is a left side view thereof;

FIG. 23 is a top view thereof;

FIG. 24 is a bottom view thereof; and

FIG. 25 is a cross-sectional view thereof taken from line 25-25 in FIG. 23.

(Continued)

FIG. 26 is a top perspective view of the second embodiment in a cuvette array;
 FIG. 27 is a bottom perspective thereof;
 FIG. 28 is a front side view thereof;
 FIG. 29 is a rear side view thereof;
 FIG. 30 is a right view thereof;
 FIG. 31 is a left view thereof;
 FIG. 32 is a top view thereof;
 FIG. 33 is a bottom view thereof; and,
 FIG. 34 is a cross-sectional view thereof taken from line 34-34 in FIG. 32.
 The broken lines in the drawings illustrate environmental subject matter that forms no part of the claimed design.

1 Claim, 34 Drawing Sheets
